UNITED STATES PATENT OFFICE.

WILLIAM EWART WATKINS, OF NEW YORK, N. Y., ASSIGNOR TO THE METALS PLATING COMPANY, OF NEW YORK, N. Y., A CORPORATION OF NEW JERSEY.

APPARATUS FOR PLATING METALS.

1,302,106.

Specification of Letters Patent. Patented Apr. 29, 1919.

Application filed June 10, 1916. Serial No. 162,977.

To all whom it may concern:

Be it known that I, WILLIAM E. WATKINS, a citizen of the United States, residing in the city, county, and State of New York, have invented certain new and useful Improvements in Apparatus for Plating Metals; and I do hereby declare the following to be a full, clear, and exact description of the invention, such as will enable others skilled in the art to which it appertains to make and use the same.

It is the object of the present invention to provide an apparatus for coating metal, and more particularly sheet metal, such as iron or steel, with a protective plating of metal, such as copper, firmly adherent to the underlying metal, free from blemishes, un-oxidized and permanent, homogeneous and uniform.

20 To attain the foregoing object, I have assembled, in a complete unitary apparatus, various mechanisms, each of which contributes to the common end, and all of which coöperate in the production of the desired 25 ultimate result, and some of which, in sub-combination and alone, present features of novelty as hereinafter claimed.

The invention comprises primarily a machine whereby sheets of elastic metal, such 30 as iron or steel, may be coated on one or preferably on both sides, with a viscous metal-plating mixture or composition. This coating is of such a character that, on subsequent heat treatment, under proper conditions, it will yield a permanent non-stripping, firmly adherent metal plating on the underlying metal.

The invention also comprises mechanism 40 for bending or curving the sheets of elastic metal before heat treatment, so that each assumes an arched shape, and for advancing or transferring the arched sheets toward the furnace, and for delivering them, properly timed, to the conveyer by which they are to 45 be transported to the furnace for heat treatment.

The invention also comprises apparatus 50 for reliably transporting the arched sheets to and through the heating furnace while in arched form, and for finally delivering them beyond the furnace, for further treatment.

The invention also comprises an improved furnace wherein the necessary heating of the articles or sheets may be carried out under

such conditions as to yield with regularity a 55 plating reliably adherent and satisfactorily free from oxidation, flaws or contamination, and in particular, free from a surface film or incrustation of iron oxid.

The invention also comprises improved 60 cooling means into which the heated articles may be delivered from the furnace and wherein their temperature is lowered in a proper and preferably non-oxidizing atmosphere.

The invention also comprises means for receiving the articles thus cooled, and flattening them, if necessary, and forwarding or transferring them, preferably automatically, for further treatment.

The invention also comprises supplemental cooling means from which the articles or sheets are in regular course delivered, preferably through an oil bath, wherein they are "fixed" or covered with a suitable protective oil of a character to prevent tarnishing during shipment or storage.

The invention also comprises improved mechanism located beyond the oil bath for such finishing and straightening as the 80 sheets may require after immersion in the oil.

The coating machine, the bending, transferring and delivery mechanism, the transporting apparatus, the improved furnace, the cooling means, the receiving, flattening and forwarding means, the supplemental cooling means, and the final finishing and straightening mechanism, all have cojoint operation and, as hereinbefore indicated, are 90 capable of regularly producing, as the result of their joint and co-operative action, flat, uniform and unoxidized plated metal sheets, (wherein, for instance, the underlying metal may be iron or steel, and the plating copper,) and wherein the plating is uniform in thickness, firmly adherent and non-stripping, of good appearance and substantially free from flaws and blemishes.

The details of one embodiment of the present invention will be made clear by the following detailed description, which is to be taken in conjunction with the accompanying drawings. I am aware, however, that the apparatus may be varied in many ways, 105 and that some of the elements described and illustrated may be replaced by equivalents, or omitted entirely, and it will, therefore,

be understood that in illustrating and describing the preferred embodiment of the invention, I do not limit myself thereto, but contemplate the employment of such other like devices in the several combinations and sub-combinations set forth, as fairly fall within the scope of the appended claims.

Figures 1 to 7, inclusive, placed end to end, constitute a sectional elevation of the complete apparatus, certain parts of the furnace being broken away between Figs. 2 and 3, and parts of the water-cooled chamber being broken away between Figs. 3 and 4, and parts of the air-cooled chamber being broken away between Figs. 4 and 5.

Fig. 7^A is similar to Fig. 7, but on a larger scale for greater clearness of illustration.

The coating machine and its coöperating bending, forwarding and delivery mechanism, shown somewhat diagrammatically in Fig. 1, are illustrated more in detail in Figs. 8 to 16, inclusive, wherein;

Fig. 8 is a sectional plan view,
25 Fig. 9 is a plan view of the feeding mechanism;

Fig. 10 is a plan view of the pusher,

Fig. 11 is a transverse section on the line 11—11 of Fig. 8,

Fig. 24 is a sectional plan on the line 24—24 of Fig. 3, showing the water-cooled 55 chamber.

Fig. 25 is a plan on the line 25—25 of Fig. 3.

Fig. 26 is a section through the sprocket of Fig. 3, over which the furnace conveyer 60 passes before dipping into the cooling bath.

Fig. 27 is a sectional elevation on the line 27—27 of Fig. 3, and Fig. 28 is a similar section on the line 28—28 of Fig. 3 but on a somewhat larger scale.

Fig. 29 is a sectional plan of the transfer mechanism of Fig. 4 on the line 29—29.

Fig. 30 shows the transfer mechanism of Fig. 4 in plan, with the box cover removed.

Fig. 31 is an elevation of this transfer mechanism as viewed from the other side 70 with certain parts in their elevated position.

Figs. 32, 33, 34 and 35 are details of the conveyer by which the sheets are transported through the air-cooled chamber of Fig. 5. 75

Fig. 36 is a sectional plan on the line 36—36 of Fig. 5, and Figs. 37 and 38 are sectional elevations on the lines 37—37 and 38—38, respectively.

Fig. 39 is a sectional plan of the coating bath shown in Fig. 6 on lines 39—39.

Fig. 40 is a sectional plan taken on the line 40—40 of Fig. 7.

Figs. 41 to 55, inclusive, show the coating machine in more detail.

Fig. 41 is a side elevation of the machine as viewed from the left.

Fig. 42 is a detail of the feeding mechanism as viewed from the right.

Figs. 43 and 44 are details of the adjusting means for the coating rolls.

Fig. 45 is a side elevation on a somewhat larger scale showing the machine as viewed from the right.

Figs. 46 and 47, placed end to end, constitute a plan view, partly in section, on the line 46—47 of Fig. 45.

Fig. 48 is a sectional elevation on the line 48—48 of Figs. 46 and 47.

Fig. 49 is a plan of the pump mechanism 100 which has been omitted from Fig. 46 for clearness in illustration.

Fig. 50 is a transverse section on the line 50—50 of Fig. 46.

Fig. 51 is a transverse section through 105 the machine on the broken line 51—51 of Fig. 45.

Fig. 52 is a section on the line 52—52 of Fig. 46, showing the drive for the converging conveyers.

Fig. 53 is a section on the line 53—53 of Fig. 46, illustrating the arched position of the sheet as it leaves the transfer mechanism of the coating machine.

Fig. 54 is a section on the line 54—54 of 115 Fig. 48, and

Fig. 55 is an enlarged view showing the chain guides for the pusher near the top of Fig. 48.

The apparatus of the present invention 120 can be used in varying ways for providing metal, (such as iron or steel) with a plating of another metal, such as copper, and while it is not possible to herein set forth in detail the permissible variations in methods, I 125 shall indicate some of those variations in describing the preferred method.

The first step in the method for which my

present invention is particularly intended, consists in applying to the articles to be plated, a coating out of which the permanently adhering or non-stripping plating 5 can be formed. If the articles are in the form of sheets, say of iron or steel, this initial coating may be applied by means of rotating rolls between which the sheets are passed, as in the machine of Fig. 1.

10 The material for use as the initial coating may vary. It should be sticky or viscous enough to adhere well to the sheets and should have body enough to form a smooth, even layer of uniform thickness. It should 15 not drip or run and of course must be so chemically constituted as to yield a plating metal when subsequently treated, as by heating. I may use a reducible compound of the plating metal held in suspension in a 20 suitable vehicle, such as a viscous reducing agent, this suspension constituting a paste or semi-liquid mixture adapted to be spread in an even, dense, compact layer upon the metal to be plated. Thus I may use oxid of 25 copper (CuO) ground to great fineness in a heavy oil such as a mixture of equal parts of Mexican crude oil and a native fuel oil. Mexican crude oil is particularly appropriate because it has an asphaltic base and 30 yields a residue of carbon on destructive distillation. In the subsequent furnace treatment, this carbon serves as a reducing agent for the metal compound present in the mixture. But Mexican crude oil alone is frequently 35 too viscous, and an admixture of native fuel oil is desirable to lower the viscosity, even though it may all, or nearly all, vaporize off during the heat treatment, and without greatly contributing to the carbon residue. In compounding such a coating 40 mixture the reducible compound of the plating metal, such as oxid of copper, must be present in such quantity that on subsequent reduction it will yield a copper plating of 45 requisite thickness.

I have found in practice that there is a limitation upon the amount of plating metal that can readily be applied by this method in a single furnace treatment. This limitation is in part due to the required viscosity of the applied coating and in part to the fact that a certain proportion of the metal compound escapes reduction because of insufficient reducing power of the reducing 50 vehicle. As a consequence, not only is the quantity of plating metal correspondingly diminished, but a portion of the reducible compound escapes reduction and must be removed from the plating surface upon which 55 it tends to collect.

Therefore, to enhance the efficiency of the process, I prefer to add as a constituent of the paste or suspension of the reducible metal compound and its liquid vehicle, an

appropriate quantity of a finely divided 65 solid reducing agent, such as finely divided carbon. The resultant mixture will still have the requisite viscosity and will also have its reducing power so increased that the metal of the reducible compound may be 70 deposited in its substantial entirety as plating metal upon the metal to be plated.

A suitable composition for the initial coating may be made by grinding together one part by weight of copper oxid, one part 75 by weight of Mexican crude oil (having a specific gravity represented by $7\frac{1}{4}$ pounds to the gallon) and $\frac{1}{16}$ to $\frac{1}{8}$ part by weight of finely divided carbon, as for instance, lamp black. Such a mass will have a viscosity 80 sufficient to permit it to be applied by coating rolls of the type shown in Fig. 1, and when so applied will form a dense, adhesive, uniform layer upon both sides of the iron or steel sheet.

35

It is possible to enrich such a coating mixture by grinding into it say one part by weight of finely divided metallic copper. The viscosity will still be satisfactory, and this additional copper will supplement that 90 resulting from reduction of the copper oxid and so yield a plating of correspondingly increased thickness.

Instead of Mexican crude oil, I may use a lighter hydrocarbon, such as kerosene, or I 95 may even employ water as the spreading vehicle, but, in these instances, I increase the amount of finely divided carbon employed so that there may be enough carbon present to effect complete reduction of the oxid and 100 to afford adequate protection to the melted or nearly melted, copper.

Also, I have discovered that it is possible to dispense entirely with the reducible compound and that the copper or other plating 105 metal may be applied to the iron or steel sheet as finely divided metal, preferably obtained by precipitation or reduction, in connection with a suitable distributing vehicle capable of holding the metal in position until it melts and forms a non-stripping plating. Finely divided solid carbon, such as 110 lamp black, may be present to protect against oxidation, when necessary, and in addition, or as a substitute for the solid carbon, a fluid hydrocarbon, such as kerosene or a viscous hydrocarbon, such as Mexican crude oil, may serve as the vehicle itself.

115

The next step in the process, whatever 120 may be the exact composition of the initial coating, consists in bending each coated sheet after it emerges from the coating rolls, so that it assumes the form of an arch, and this I am able to do by the apparatus of Fig. 1, without disturbing the continuity of 125 the initial coating, by the effective expedient of giving the sheet an upward bend or hump in the middle, particularly at its

front edge, and then pressing inward on its edges until the sheet bows up and assumes the desired arched form. The whole operation is automatic in the apparatus of Fig. 1, 5 and the sheet is then ready for forwarding to the furnace for the necessary heat treatment.

The next step is the heat treatment within the furnace whereby the initial coating 10 yields a non-stripping or firmly adherent plating on the underlying iron, steel or the like. The furnace of Fig. 2 is sealed against the free circulation of air and in it the sheets as they pass through on an endless 15 conveyer, are heated in a reducing environment to a temperature and for a time sufficient to produce such reduction, or melting, or both, as may be necessary to form the plating from the materials of the initial 20 coating. A temperature of 2000° Fahr. or thereabouts, applied for 20 to 60 seconds is sufficient when the plating is to be copper on iron or steel. For a coating of tin on iron, the temperature would be correspond- 25 ingly varied. By heating in a reducing environment, no superficial layer of iron oxid forms over the copper plating as may be the case when heating in an open gas flame or in an oxidizing atmosphere.

30 Progressively the arched sheets are moved along through the furnace and are ultimately passed into the water-cooled chamber of Fig. 3, where their temperature and that of their conveyer is gradually lowered.

35 The sheets are finally delivered from the conveyer to the receiving apparatus of Fig. 4, where they are automatically forwarded and flattened in a non-oxidizing and cooling environment, and then delivered to another 40 conveyer which carries them through the air-cooled chamber of Fig. 5 into and through the oil bath of Fig. 6, and finally delivers them to the finishing apparatus of Fig. 7.

45 Both cooling chambers are carefully sealed against the entrance of air, and a substantially non-oxidizing atmosphere is thereby maintained throughout practically all of the heated parts of the apparatus, including the 50 furnace muffle. This is of importance in producing a plating free from contamination and, in particular, free from a surface film or incrustation of iron oxid on the top of the plating of copper or the like.

55 *The coating machine.*

(Figs. 41 to 55.)

The coating machine comprises a frame 60 100, and is provided at the front with an apron or feed table 101 on which the sheets to be coated are dropped by hand and from which they are automatically fed into the coating rolls.

The automatic sheet feeding mechanism 65 comprises three stops 102, (Figs. 46 and 50) in the form of rollers which project above the feed table, and may rotate about their respective axes while contacting with the edge of a sheet during its forward move- 70 ment. As a means for holding the sheet against these rollers 102 and bringing it into true alinement for passage through the machine, there is provided a roller 103 mounted on an arm 104, which is pivoted 75 beneath the feed table on pivot 105, and is actuated by a link 106 adjustably pivoted to arm 104 and also pivoted to a swinging arm 107, the rear end of which is pivoted to the under-face of the feed table at 108, and the 80 front end of which carries a roller 109 actuated by a cam 110, the movements of which are hereinafter described. A rigid and stationary reinforcing strip 111 gives firm anchorage for pivots 105 and 108, and 85 a spring 112 is connected between this strip 111 and swinging arm 104 to yieldingly urge roller 103 toward rollers 102, so that on suitable movement of cam 110, the roller 103 can swing inward against the edge of 90 a sheet that has been dropped on the table and slide that sheet over against rollers 102 and thereby bring it into proper position and alinement with respect to the coating 95 rolls.

The coating rolls 113 and 114 (Fig. 48) are faced with a layer 115 of suitable yielding composition like soft rubber. The shafts 116 and 117 for these rolls are carried in bearing blocks 118 and 119, respectively, 100 (Figs. 41 and 51) the lower pair of which are seated at the bottom of appropriate guideways in frame 100, and the upper pair 118 of which are adjustable up or down in that guideway to vary the distance between 105 the coating rolls 113 and 114.

The adjusting mechanism for the coating rolls comprises a pair of springs 120 (Fig. 51) located respectively within the guideways of frame 100, and positioned between 110 the adjacent bearing blocks 118 and 119 of the upper and lower roll shafts. These springs tend to hold the coating rolls separated. Above each upper bearing block 118 and contacting therewith is a stop bar 121, (Fig. 41) which passes freely through a cover-plate 122 (Fig. 43), except that it has a longitudinal slot 123 (Fig. 44) in which fits a key 124 (Fig. 43) rigidly mounted in cover-plate 122. The upper end of rod 121 is threaded and passes freely through an enlarged opening in a worm gear 125 and has threaded engagement with a nut 126 which is adjustably and detachably connected with worm gear 125 by bolt 127 and slot 128 (Fig. 44). A bracket 129 (Fig. 43), integral with cover-plate 122, forms a guide and support for the upper end of rod 121. 120 125

- Engaging with worm wheel 125 is a worm 130 fastened to a shaft 131 which carries an adjusting hand wheel 132 (Fig. 41) on the left hand side of the machine. This shaft 131 extends across to the other side of the machine (Fig. 51), for actuating another and similar worm wheel and stop bar to hold the other upper bearing block against the tension of its spring 120. The upper coating roll can thus be adjusted toward or from the lower roll and each end can be independently adjusted to maintain proper spacing of the rolls throughout their entire length.
- 15 The liquid composition to be supplied to the coating rolls is pumped through a transverse pipe 133 and delivered through narrow longitudinal slots and in a substantially continuous cascade or sheet to a distributing roll 134 which is accurately spaced a short distance from the uppermost coating roll 113 (Fig. 48), and is spaced slightly from an equalizing roll 135. Distributing roll 134 is carried and driven by a shaft 136, and 20 equalizing roll 135 is carried and driven by a shaft 137, and the ends of these shafts 136 and 137 are fitted to bearing blocks 138 and 139, respectively, (Fig. 41). These blocks are mounted in horizontal guideways as 25 shown. A pair of springs 140 urge the distributing roll 134 away from the coating roll 113, and a similar pair of springs 141 urge the equalizing roll 135 away from the distributing roll 134. Opposed to each 30 spring 140 and 141 is a stop bar complete with nut, gears and other features, of the type shown in Figs. 43 and 44, and complete with hand wheels 142 and 143. The ends of each roll can thereby be adjusted 35 simultaneously or one end can be shifted independently of the other. One of these stop bars controls the distance between the distributing roll 134 and the coating roll 113, and the other controls the distance between 40 the distributing roll and the equalizing roll 135, and jointly they control the thickness of the film of fluid which is carried forward by the distributing roll and deposited on the upwardly moving face of the upper coating 45 roll 113.
- In practical operation, the coating fluid may work out to the edge of the distributing roll 134 and to the edge of the equalizing roll 135 and there harden to form a fin, 50 and to prevent this troublesome accumulation, there is provided at each end of these rolls a scraper 144 in the form of a shallow, concave box, the curved bottom of which contacts with the ends of the rolls 55 and approximately intersects their line of contact one with another, as shown in Fig. 48, and so act somewhat as a receptacle in which these incrustations may be accumulated and from which they may be removed 60
- from time to time. This scraper 144 is 65 rigidly attached to an arm 145 fastened with a set screw 146 to the fluid distributing pipe 133.
- The lower coating roll 114 is similarly equipped with a distributing roll 147 and 70 an equalizing roll 148, these being adjustable, respectively, by means of hand wheels 149 and 150 (Fig. 41) acting through worm gears, stop bars, and other elements, as in the case of the upper equalizing and distributing rolls. The scraper 151 for the lower distributing roll 147 is of essentially 75 the same shape as scraper 144, but is arranged to clean the end of the lower coating roll 114 as well as its distributing roll 80 147, the concave bottom of the scraper 151 substantially intersecting the line of contact of these two rolls. This scraper 151 is supported from the lower fluid supply pipe 152 and can be swung thereon for emptying 85 when desired.

Liquid mixer and distributor.

(Figs. 41, 48 and 49.)

90

The coating liquid or composition is normally held in a tank 153. As the liquid may carry suspended solids, liable to settle out, there is provided an agitator for constantly stirring the contents of this tank. The agitator comprises a central shaft 154 (Fig. 41) which carries a pair of propeller blades 155 suspended just above the bottom of the tank and adapted particularly to prevent the accumulation of solids on the bottom. 95 Agitator shaft 154 is supported in a bearing 156 (Fig. 49) carried by the skeleton cover 157 of the tank and removable from the tank with that cover for cleaning or inspection. Agitator shaft 154 carries at its upper end 100 a bevel gear 158 which meshes with a bevel gear 159 carried on a horizontal shaft 160, which is driven through a spur gear 161. The latter is driven in a manner hereinafter described. At the other end of shaft 160, 110 and splined thereon, is a spur gear 162 (Fig. 49), and this meshes with a gear 163 to drive the shaft 164 of a gear pump 165 of usual construction. Shaft 164 is squared at its exposed end to receive a hand crank, 115 and by sliding spur gear 162 outward out of mesh with gear 163, this hand crank can be used for rotating the pump to prime it, or for distributing fluid in small quantity 120 through the distributing pipes when the coating machine is not in regular operation. Gear 162 is normally held against accidental sliding movement by a set screw 166. The pump 165 and its associated gearing are mounted on one arm of the removable skeleton cover 157, and so are readily removable 125 for inspection or repair.

Pump 165 delivers the coating liquid

through a pipe 167 (Fig. 48) which at its forward end, has a branch running through valve 168 to the liquid distributing pipe 152, and also a branch extending upward 5 through valve 169 to the upper distributing pipe 133. At a point approximately above tank 153 the liquid distributing pipe 167 has a by-pass through valve 170 and a pipe 171 leading back to tank 153. For 10 purposes of priming it is therefore possible to open valve 170 and close valves 168 and 169, and then by hand or otherwise, pump the liquid out of tank 153 and through valve 170 back into the tank again, thereby mixing 15 and agitating the liquid and making sure that the pump is in proper operative condition. A union 172 in pipe 167 facilitates removal of tank 153 and its detachable cover, pump, gearing, and the like.

20 To take care of the surplus liquid, there is provided beneath equalizing roller 137 a removable trough 173 (Fig. 48) which slopes (Fig. 51) to a drain pipe 174 (Fig. 48) discharging into tank 153, and, similarly, the lower equalizing roll 148 has a removable, sloping trough 175 with a drain pipe 176. These two drain pipes, as well as pipe 171, are short enough not to interfere with removal of tank 153. An inclined 25 drain plate 177 is detachably supported under the lower coating roll 114 to catch the drippings and deliver them into trough 175.

30 Referring to Figs. 41, 45, 46 and 51 the driving mechanism for the coating machine and its supply pump is disclosed. Power is delivered through a main driving chain 178 (Fig. 45) to rotate a sprocket 179 loosely mounted on a shaft 180. The outer face of the hub of sprocket 179 is shaped to form a 35 clutch member and an opposing clutch member 181 is splined on shaft 180 and provided with a vertical shipper lever 182, pivoted at 183 to a bracket 184, secured to the frame 100. For the purpose of actuating the clutch 40 from the other side of the machine, there is provided a connecting link 185 pivotally attached to shipper lever 182 and to a corresponding lever 186 on the other side of the machine. The spline for clutch member 181 45 abuts against the hub of sprocket 179 and holds it against axial movement, and the right hand end of shaft 180 is supported in an outboard bearing 187 in the form of a bracket bolted to frame 100 (Figs. 45 and 46). The shipper lever 182 is of yoke shape 50 (Fig. 45) to straddle shaft 180, and is attached through horizontal lugs to a split collar 188 seated in a groove of clutch member 181. The left hand end of shaft 180 carries 55 a hand wheel so that the machine can be turned over slowly by hand, as when adjusting the timing of its several parts.

60 Keyed to shaft 180 is a gear 189 (Fig. 51) which meshes with a gear 190 on shaft 117 65 of the lower coating roll. Gear 190 meshes

with a gear 191 (Fig. 45) supported on a stub carried by a bracket secured to the right hand side of the machine. Gear 191 meshes with a wide gear 192, similarly supported and the latter meshes somewhat loosely with 70 a gear 193 on shaft 116 of the upper coating roll. Gear 193 meshes somewhat loosely with a gear 194 on shaft 136 of the upper distributing roll and drives that roll at a proper peripheral speed to effectively apply 75 the coating liquid to the yielding face of the upper roll. Gear 194 meshes with a gear 195 on shaft 137 of the upper equalizing roll to rotate it at the same peripheral speed as the adjacent distributing roll.

80 The lower distributing and equalizing rolls are similarly provided with driving gears 196 and 197, respectively, and are driven from gear 190.

85 When the machine is in action, the power delivered through main driving chain 178 and its sprocket 179 and the co-operating clutch, drives the coating rolls 113 and 114 as indicated by arrows Fig. 48 and a sheet of metal A, moved forward on the feed table 101, will be gripped at its forward edge by the yielding composition faces of these rolls, and drawn forward, simultaneously with the deposition on its top and bottom faces of 90 a thin, uniform and homogeneous film of 95 the coating liquid. One side may be left uncoated if desired.

100 The mechanism whereby the sheet of metal to be coated is automatically fed forward into position to be gripped by the coating rolls, comprises a finger 198 (Figs. 42 and 46) which projects through a slot in feed table 101, and is carried by a block 199 mounted to slide in guides 200 (Fig. 50), secured to the under face of feed table 101. 105 As a means for sliding block 199 toward and from the coating rolls, and for timing its movements, there is provided a link 201 (Fig. 42) pivoted to the block and adjustably pivoted to a swinging arm 202, which 110 is mounted near the center of a transverse rock shaft 203 supported by bearings on the front legs of frame 100. The right hand end of shaft 203 carries a crank 204, to the slotted end of which is adjustably connected 115 a cam actuated thrust bar 205, which carries a roller 206 bearing against the periphery of a cam 207, and this, as shown in Fig. 51, is mounted on shaft 180 at the side of gear 189. The cam is fastened to gear 189 by a 120 bolt 208 (Fig. 42) which can be shifted in a slot 209 to permit adjustment of the cam with respect to the gear to regulate the timing of the feed mechanism with respect to other moving elements of the machine. 125 Thrust bar 205 has its rear end formed into a yoke 210 which embraces and slides upon the hub of cam 207 and swings thereon as it moves outward under the action of the cam. To effect inward movement of the thrust bar 130

205 and forward movement of the feeding finger 198, shaft 203 is provided with a downwardly extending crank 211, to the end of which is pivoted a rod 212, Fig. 45 the rear end of which passes freely through a block 213 which is mounted on the main frame and is free to swing as much as is necessary to accommodate backward and forward movements of rod 212. A compression spring 214 encircles rod 212 and bears at its rear end on block 213, and at its forward end against a tension adjusting nut 215. Outward movement of thrust bar 205 produced by action of cam 207 on roller 206 compresses spring 214 and as soon as cam 207 will permit, spring 214, by its expansion, yieldingly pulls feed finger 198 forward toward the coating rollers and thereby advances the sheet to be coated until its front edge enters between the coating rolls. The sheet-aligning mechanism for the feed table, heretofore described, is suitably timed with respect to the forward movement of finger 198 by proper location of cam 110 with respect to sliding block 199 to which it is rigidly fastened.

To drive pump 165 and its associated agitator, there is provided a sprocket 216 (Fig. 51) on shaft 117, the sprocket being bolted to gear 190. A chain 217 driven by this sprocket passes over a smaller sprocket 218 (Fig. 46) secured to a shaft 219 (Fig. 52), which extends substantially across the machine and also serves to drive the converging conveyers as hereinafter explained.

Keyed to the shaft 219 is a spur gear 220 (Figs. 52 and 46) which meshes with gear 161 (Fig. 49) of the pump-driving mechanism. In this way, power is delivered to the pump.

Arching transfer and delivery mechanism.
(Figs. 41, 45, 46, 47, 48, 52-55.)

Immediately behind the main frame 100 is an auxiliary frame 221, whereon is mounted the mechanism by which the flat sheets as they come from the coating rolls are bent into arched form and then are forwarded and are delivered at regular and predetermined time intervals to the conveyer by which they are transported to and through the furnace of the apparatus. To the front of frame 221 are attached a pair of supports 222 and 223, which are anchored and supported at their forward ends by bolted connection with main frame 100. A single bolt 224 for each support is used, thereby serving as a hinge to compensate for slight differences in the height or alinement of the two frames. The rear end of each of these supports is similarly secured by a single bolt 225.

The means for bending each sheet into an arch, includes a plurality of rotating shafts 226, of which there may be five, as shown,

having their bearings in supports 222 and 223. Each of these shafts carries a sprocket 227 and all of the sprockets are positively driven through a single chain 228 which passes over an idler 229 and is driven by a sprocket 230 (Fig. 52) mounted on shaft 219 and driven thereby. Shafts 226 are provided with star wheels or the like, preferably in the form of thin disks having sharp edges with teeth, to limit the area of their contact with the coated sheet as it is advanced over them. The star wheels 231 for the first two shafts of the series are fastened to those shafts and so are positively driven, and similarly, the four outside star wheels 232 of the next two shafts are positively driven. The two outermost star wheels 233 of the last shaft are free to rotate on their shaft, but are held against axial displacement by a pair of collars, one of which can be adjusted axially along the shaft. All of the star wheels so far described are preferably of the same diameter, but the three central star wheels 234, 235 and 236 on the three rear shafts are of progressively increasing diameters, as shown in Fig. 48, and are loose on their respective shafts. They are held against axial shifting by the collars between which they are free to rotate, and they are staggered as shown in Fig. 46.

When a coated sheet comes from the coating rolls, it is carried along by the star wheels, and their points of contact with it are so small in area as not to wipe off or deface the adhering coating to any appreciable extent. As the sheet moves along, its center rides up on the enlarged central wheels 234, 235 and 236, which are driven by the friction of the sheet thereon and thus is given a hump in the center preparatory to engagement with the converging elements which transform the sheet into a complete and symmetrical arch.

Above frame 221 and supported thereby are a pair of converging elements in the form of belts or the like 237 and 238, preferably of leather and each passing over pulleys 239 and 240. These pulleys are so spaced, as shown in Figs. 46 and 47, that the belts converge and collectively form a conveyer by which the sheets are received from the star wheels and are held by their edges only. The edges are then progressively squeezed inward as the sheets are advanced between the converging belts thereby converting the sheets into the desired arched form for delivery to the furnace conveyer.

In considering the details of the converging conveyer, reference may be had to Figs. 11, 12, 13, 46, 47, 48, 52 and 53.

Each of the leather belts 237 and 238 has a facing of separated metal plates or scales 241 (Fig. 12), and each of these scales has two integral legs, one of which is riveted to

the belt and the other of which is L-shaped as shown to form a shelf 242 in the acute angle of which the edge of a sheet of metal under treatment may be received and under 5 the overhanging but somewhat yielding side of which that edge is held against danger of accidental dislodgment.

These belts 237 and 238 are driven, respectively, by their pulleys 239 (Fig. 52). The 10 pulleys are mounted, respectively, on vertical shafts provided with beveled gears 243 which mesh with beveled gears 244 splined on shaft 219 and driven thereby. Each of these pulley shafts passes through a bearing 15 member 245 from which depends a downwardly extending bracket 246 terminating in a bearing 247, whereby shaft 219 is supported and the adjacent beveled gear 244 is held to working engagement with its companion gear 243. The bearing members 245 for the belt pulleys 239 are supported by a cross-bar 248 (Fig. 53). Each bearing member 245 has a slotted lug 249 equipped with a clamping stud 250 threaded into 20 cross-bar 248. It is therefore possible to shift either of the pulleys 239 to the right or to the left, as to increase or decrease the distance between them, or to correct for misalignment in the machine.

30 As a means for guiding the working sides of the conveyer belts 237 and 238, and to prevent them from sagging or from bulging outward under the spreading action of the arching sheets, two angle bar guides as 251 and 35 252 (Fig. 47) are provided on the horizontal flange of each of which the lower edge of its leather belt may slide in a shallow groove. The scales 241 of the belts also contact with and slide along these horizontal flanges 40 (Fig. 53). Guides 251 and 252 are bolted respectively to ears 253 and 254 (Fig. 53) integral with lugs 249 of the pulley bearing members 245. Guides 251 and 252 have slots 255 and 256 (Fig. 46) to permit longitudinal shifting, when required, (their other ends being similarly slotted, Fig. 47) and can be swung through a small angle about the bolts 257 and 258 which pass through these slots and anchor the guides to 50 ears 253 and 254 (Fig. 53).

At the other end of this converging conveyer, the pulleys 240 (Fig. 47) act merely as sheaves and are mounted on vertical shafts, each of which is carried in a bracket 55 259 bolted to a cross-bar 260 of the supporting frame 221, and having a slot 261 at its clamping bolt to permit adjustment inward or outward to vary the distance between the two conveyer belts at the narrow end of the 60 conveyer. Cross-bar 260 is also adjustable lengthwise of the machine to move pulleys 240 to tension the conveyer belts. This latter adjustment is effected by means of screws 262, one on either side of the machine, and 65 threaded through studs 263 which are

screwed into the top of frame 221. These screws bear against the edge of bar 260 and can be used to force the bar rearwardly when the belts are to be tightened. Bolts 264 pass through slots in bar 260 and serve 70 to anchor the bar to frame 221 after the adjustment is complete.

Beyond the narrow end of this converging conveyer is a guideway consisting of two independent bent plates 265, each of which 75 is pivoted by a bolt 266 to a bracket arm 267. This bracket arm has a slot and clamping bolt at 268 to permit swinging adjustment of plate 265 about bolt 266. At the other end of the bracket arm 267 is a pivot bolt 269 80 and a clamping bolt 270, the former passing through a longitudinal slot in arm 267, and the latter through a similar slot in that arm, and also through a curved slot in cross-bar 260, so that bracket arm 267 can be adjusted longitudinally, or can be swung about bolt 269 as a center, to bring its plate 265 into best relation to the delivery end of the converging conveyer. Plates 265 are thus adjustable toward or from one another to 85 vary the width of the guideway formed therebetween.

By the apparatus above described, the sheets of metal to be treated, as they come from the coating rolls, are given an initial 95 bend by the star wheels, and then pass along through the converging conveyer, and when they issue therefrom into the stationary guide, formed by plates 265, they are in proper condition for delivery to the furnace 100 conveyer. In order that there may be no uncertainty in their delivery from the converging conveyer to the furnace conveyer, and in order that their delivery may be definitely timed, there is provided a delivery 105 mechanism or pusher, shown particularly in Figs. 41, 45 and 48.

The pusher comprises a pair of endless chains 271 passing over driving sprockets 272 fastened to shaft 273, which is mounted in 110 brackets 274 bolted to supports 222 and 223. This shaft carries a sprocket wheel 275 driven through a chain 276 by sprocket 277 (Fig. 51) keyed to shaft 180. Pusher chains 271 also pass over smooth flanged pulleys 115 278, which are loosely mounted on a shaft 279 supported by brackets 280 which are bolted at the top of frame 221 (Fig. 45). These brackets have slots 281 and adjusting screws 282 to permit them to slide with respect to frame 221, and so tighten or loosen the pusher chains 271.

Chains 271 are provided with three L-shaped pushing fingers 283, each mounted on a pivot pin 284. These pivot pins tie the 125 chains together, as shown in Fig. 55, so that they move in unison, but the chains are spaced apart for enough to permit swinging movement therebetween of the shorter arm of each L-shaped finger 283, whereon a 130

cam roller 285 is mounted. The cam surface on which these rollers 285 bear, comprises a top plate 286 (Fig. 48), a bottom plate 287, and a stationary curved casting 288, mounted on shaft 279. This casting serves as a space block for the two chain pulleys 278 and is connected by slots and bolts to plates 286 and 287 to permit longitudinal adjustment of those plates, when desired, as when brackets 280 are shifted to tighten or loosen the chains 271.

Brackets 274 extend beyond shaft 273 for attachment to horizontal tie-bars 289 and 290 (Figs. 48 and 54), and these serve as supports for vertical angle plates 291 and 292 (Fig. 54) from which as shown in Fig. 48, brackets 293 extend forward and upward and brackets 294 extend forward and downward for attachment to circular guard strips 295 which cover the driving sprockets on shaft 273, and also extend beneath plate 287, but spaced therefrom, to form guiding channels for the chains 271 and the pusher fingers, as shown in Fig. 55.

25 Tie-bars 289 and 290 also support brackets 296 and 297 fastened by bolts and slots to permit their independent vertical adjustment, and it is to these brackets that the forward ends of the top and bottom cam plates 286 and 287 are attached, and by which their distance apart at their forward ends can be adjusted. These plates are cut away or narrowed at their extreme forward ends sufficiently to clear driving sprockets 272 between which they pass, as shown in Fig. 54.

When the pusher is in action, the L-shaped fingers travel with the same, or nearly the same, lineal speed as the converging belts, and when properly timed, will be in contact, or nearly so, with the sheets while they are being bowed into arched form by the converging conveyer. It is, however, the particular function of these fingers to give a positive transference or delivery of the arched sheets from the discharge end of the converging conveyer and over guide plates 265 and onto the furnace conveyer by pressing or striking against the rear end of the sheet as soon as it comes to rest in the stationary guides, or even before it has come to rest, if desired. By having these fingers provided with cam rollers, as shown and described, each roller will keep its finger in substantially vertical position until after it moves out of contact with the arched sheet, for as shown in Fig. 48, the pushing finger leaves contact with the delivered sheet by a substantially vertical movement induced by the shape of the curved cam casting 288 on which its roller 285 bears. This eliminates any tendency to lift or kick up the rear end of the arched sheet, and leaves the sheet reliably gripped by the furnace conveyer. Because of this arched shape and therefore somewhat tensional condition, the sheets,

even if of thin metal, do not sag or collapse when subjected to the high heat of the furnace.

The furnace.

(Figs. 2, 3, 21, 22 and 23.)

70

The furnace comprises a masonry foundation 300 on which are metal channels 301 stacked flange to flange one above another, and connected together at their ends by vertical angle plates 302 (Fig. 21) to form a rectangular housing within which are the heat resistant elements of the furnace. On foundation 300 are skews 303 and an arch 304 to form a conduit 305 through which the furnace conveyer may return toward the coating machine. Above arch 304 are skews 306 and rectangular fire brick abutments 307 recessed on their inner faces to form vertical flues 308 (Figs. 21 and 23). Above 80 abutments 307 are skews 309 and fire brick arches 310, and the skews are cut away and the arches spaced apart to form upward continuations of the flues 308, but below arches 310 and above arch 304 is a long 90 chamber (see Fig. 2) which may be designated as the combustion chamber of the furnace. Liquid fuel is supplied to this chamber by an atomizer 311 (Fig. 2), working in usual manner in conjunction with an air 95 blast nozzle 312. The combustible mixture is delivered into a square duct 313 where ignition takes place, and from which a long and very hot flame is projected rearwardly through the combustion chamber. A baffle 100 or deflection wall 314 (Fig. 2) may lie in the direct path of the flame to assist in effecting complete combustion. The floor of the combustion chamber may be made level by filling in with masonry at 315 (Fig. 23), 105 flush with arch 304. The rear end of the combustion chamber is closed by a bag wall 316, beyond which, in the apparatus here illustrated, is another combustion chamber of like size and construction, heated by a 110 burner at its remote end, as shown in Fig. 3.

Above skews 309, the metal housing of the furnace is lined with a fire brick wall 317, skews 318 and a top arch 319, and over this arch is a packing of sand 320 which may be 115 easily removed in case it becomes necessary to take down arch 319, as for gaining access to the interior of the furnace when repairs are to be made. Attached to the lining 317 are fire brick abutments 321 which overlie 120 arches 310 and are spaced apart, as shown in Fig. 21, to form vertical extensions of the flues 308. On these abutments 321 is placed the long refractory muffle 322 through which the furnace conveyer passes. A spacing 125 block 323 may be located on the crown of each arch 310 to assist in the support of the muffle, but between this block and the adjacent abutments 321, are passages 324 which extend continuously over arches 310 from 130

the front of the furnace to its rear bag wall, and thereby give free circulation of the flame and products of combustion under and about muffle 322. The sides and top of the muffle 5 are entirely exposed within the long unobstructed heating chamber 325, which is roofed by arch 319, and into which the flames 308 terminate at their upper ends. Vents 326 lead from this heating chamber to the 10 outside of the furnace and through these the products of combustion may escape to appropriate stacks. There is provided a duct 327 which passes through arch 319 and through a distance block 328 and the top of 15 the muffle 322 so that a pyrometer may be introduced into the muffle for temperature determinations. This duct is normally closed but it can be used as an exit for the muffle gases, when desired, as when they 20 might otherwise blow out at the intake end of the muffle.

It is desirable that the muffle shall be protected as much as possible from the access of air, and to this end the front end of the 25 muffle is partially closed by a fire brick curtain 329 (Fig. 2), with an opening there-through and through the adjacent metal end plate 330 (Fig. 2) just large enough to permit free movement into the furnace of the 30 conveyer and its load of arched sheets. At the intake end of the muffle, the end wall of the furnace may be stepped, as shown in Fig. 2, with a cast iron bed plate 331, forming a delivery platform, and interlocking with 35 the end channels of the furnace housing to give rigidity to the structure. The exit end of the muffle is partially closed by a fire brick curtain 332, which is reinforced by a cast iron end plate 333, to which the water cooled 40 chamber is attached.

The water cooled chamber.

(Figs. 3, 4, 24, 27 and 28.)

45 The water cooled chamber into which the heated plates are carried from the furnace muffle, is made up of cast iron sections fastened end to end and each having an inner wall 334 and an outer wall 335 (Fig. 28), 50 with flanges 336 at both ends by which the section is bolted to adjacent sections. The joints are made air tight with asbestos or other packing. The sections are approximately rectangular in cross-section (Fig. 55 27) and provided at the top with a hand hole 337 and at the bottom with a similar hand hole 338. The inner wall 334 has an upstanding integral web 339 intersecting the upper hand hole 337, and forming a baffle or 60 partition.

Immediately over hand hole 337, is a casting 340, having an intake conduit 341, to which cold water may be admitted through a supply pipe 342, for circulation between the 65 walls 334 and 335 of the cast iron section to

an outlet conduit 343 which discharges into the outlet pipe 344. As shown in Fig. 3, the top casting 340 has lateral passages leading to separate inlets which are spaced apart and separated by the intervening wall 345. 70 The incoming water is thus delivered near the ends of the section, and there is deflected by the baffle 339, so that it passes completely around the section on its way to the outlets, which are multiple and spaced apart 75 the same as the inlets.

As a means for drawing off the water from the sections as for cleaning, or when the apparatus is to be shut down in cold weather, the covers 346 for the bottom hand 80 holes 338 are each equipped with drain nipple 347, leading to a drain pipe 348, by which the water may in such an emergency be carried off to a sewer. In the embodiment illustrated, the cold water supply pipes 85 342 all receive their water from a common water main 349, and the hot water from all the sections discharges into a single discharge main 350.

Within the cooling chamber formed by 90 this plurality of water cooled sections, the furnace conveyer and its supported metal sheets, are cooled below a red heat. The sheets are then discharged at the transfer mechanism illustrated in Fig. 4. As the water cooled castings of this chamber will expand and contract somewhat, as the temperature within the chamber varies, they are so supported that such axial movement as may occur, will not tear them from their 95 fastenings. To this end they are provided, as shown in Fig. 28, with laterally extending lugs 351, which rest on, but are not bolted to, horizontal supporting channels 352, thereby leaving the sections free to shift 100 105 endwise if the temperature conditions should require it. Channels 352 are suitably supported on a structural steel frame 353 (Fig. 27).

Transfer mechanism.

(Figs. 4, 29, 30 and 31.)

The transfer mechanism of Fig. 4, whereby the partially cooled sheets are stripped from the furnace conveyer, is housed within a double walled box between the walls of which cooling water may be circulated. 115

Each end of this box consists of a single casting having an outer wall 354 and an inner wall 355, and the bottom of the box is formed of two double walled castings 356 and 357, each of which rests on integral supporting and stiffening webs 358. The top or cover of the box consists of two double 120 125 walled castings 359 and 360, either or both of which may be removed from the box without disturbing the other walls or the contents of the box. All of the castings which form this box are bolted together to 130

form a substantially air-tight compartment within which the transfer mechanism is adequately housed.

Each of the castings of the box has a water inlet and a water outlet, not shown, through which the cooling water can be circulated. Within this water-cooled box is a supporting frame 361 on which are mounted two trains of flattening rolls 362 and 363 of known construction. There is also a receiving means comprising a bracket 364 on which is a framework supporting an inclined apron 365. This apron is in the form of a shallow trough open at its lower or discharge end, where it feeds the plates into the flattening rolls. It has at its upper end a protruding nose 366 rising above the bottom of the apron and acting as a stripper to detach the cooled sheets from the furnace conveyer. Each sheet is delivered to the apron in arched form, but as it slides down the apron it tends to flatten out of its own weight. The tapering nose 366 prevents premature flattening or transverse kinking 25 of the sheet.

To assist the stripping action of the apron, but more particularly to insure a positive and accurately timed feeding of the sheets into the flattening rolls 362 and 363, there is provided pushing mechanism comprising two parallel endless chains 367 tied together by cross-bars 368, near the outer ends of which are carried pushing fingers 369, of which four pairs are used. These fingers 35 engage the arched sheet relatively near the edges of the sheet and so do not interfere with the collapse of the arch when the sheet slides down apron 365. The fingers continue their engagement with the sheet until 40 it has been advanced far enough into flattening rolls 362 to be gripped by those rolls and needs no further pushing from behind.

Pusher chains 367 are supported by front sprockets 370 and rear sprockets 371, and 45 are driven by larger sprockets 372 mounted on a shaft 373 which has its bearings in ears 374, depending from a pair of floating arms 375, which are pivoted on a shaft 376, the ends of which are provided with fittings 377 50 which may seat upon or be lifted from contact with stop plates 378 bolted to the side of the box.

Beneath each stop plate 378 is a bracket 379 bolted to the side of the box and having 55 a pivot 380 on which is mounted an inclined link 381. The front or upper end of these two links are connected by a cross-bar 382 and this cross-bar is fastened to the two floating arms 375. The front ends of these 60 arms rest on stops 383. At the other end of arms 375, and serving as a bearing for shaft 376, is a pair of links 384 loosely mounted on a shaft 385, the ends of which are seated in bearings 386 secured to the side 65 walls of the box.

Secured to shaft 376 at one of its end fittings 377 is a chain 387 which passes upward over a sprocket 388 and is secured to a counterweight 389. Sprocket 388 is secured to a shaft 390 which extends through 70 the left hand wall of the box and carries a sprocket 391 which can be driven through a chain 392 from a sprocket 393, to which is attached a winding handle 394 and a holding ratchet 395.

The pushing mechanism above described is driven through indirect connections with the furnace conveyer. These connections include a sprocket wheel 396 (Fig. 4) on the tail shaft 397 of the furnace conveyer and a 80 chain 398 (Fig. 31) on the outside of the water-cooled box. This chain drives a sprocket 399 loosely mounted on a transverse shaft 400 to which it can be operatively connected by a hand operated clutch 401. 85 Shaft 400 drives the two trains of flattening rolls. It carries a spur gear 402 (Fig. 29) meshing with a pinion 403 on a stub shaft which carries a spur gear 404 meshing with a pinion 405 on a second stub shaft to the 90 other end of which is connected a sprocket 406 over which passes a drive chain (indicated by dotted lines Figs. 4 and 29), whereby the sprockets 407 and 408 of the flattening rolls are driven.

Shaft 400 also drives the pusher, for it carries a pinion 409 (Fig. 29) meshing with a spur gear 410, to the side of which is fastened a sprocket 411 over which passes a chain 412 running up to a sprocket 413 on 100 shaft 385. Shaft 385 carries a second sprocket 414 (Fig. 30) connected through a chain 415 to a sprocket 416 on shaft 376, and the latter carries a sprocket 417 connected through a chain 418 with a sprocket 105 419 on shaft 373. With the furnace conveyer running, the flattening rolls and their cooperating pusher can be started or stopped at will by manipulation of the hand clutch 401.

A pair of glazed windows 420 and 421 (Fig. 4) are provided in the water-cooled box near hand clutch 401 through which the operations within the box may be watched, and if anything goes wrong, it is possible 115 with hand crank 394 to elevate the pushing mechanism out of engagement with the sheets being delivered and allow those sheets to be received by apron 365 on which they will stack up. Such lifting of the pushing apparatus may take place even when the pusher is being driven through its connections with the furnace conveyer.

If access to the flattening rolls becomes necessary, as for adjustment or repair, the 125 water-cooled covers 359 and 360 may be unbolted and taken off and the pusher mechanism swung up through the opening to give easy access to the parts beneath, even though the furnace conveyer be maintained in mo- 130

tion to prevent over-heating of it within the furnace.

After the furnace conveyer delivers its sheets to the receiving and transfer mechanism, of Fig. 4, by passing over sprockets 422 on tail shaft 397, it returns toward the furnace through a second water-cooled chamber (Fig. 3) which terminates in a sheet metal hood 423, the particular function 10 of which is to seal the water-cooled chambers and the water-cooled box from air which might otherwise work back progressively toward the muffle and cause oxidation of materials under treatment. Hood 423 is of 15 rectangular cross-section (Fig. 27), and is supported by the adjacent water-cooled chamber. Passing through hood 423 is a shaft 424, the outer ends of which are carried by bearings supported on angle bars 20 425 bolted to the structural steel frame 353. The lower end of this hood 423 is guided by transverse angle bars 426 through which it is free to slide in accordance with its thermal expansions or contractions. The lower 25 end of the hood dips beneath the surface of a body of water 427 held in a suitable concrete tank.

Shaft 424 carries a pair of sprockets 428 of special design, as shown in Fig. 26, to 30 accommodate the flights of the furnace conveyer when the conveyer makes its reverse bend (Fig. 3) preparatory to passing downward into the bath of water wherein the chain is cooled before returning toward the 35 front of the furnace. To prevent entrance of air to the hood, stuffing boxes 429 are used around shaft 424 (Fig. 27), and a steam outlet pipe 430 leads from the hood near its top. A water seal or suitable exhausting 40 mechanism may be connected to pipe 430 to prevent a back draft of air.

The air cooled chamber.

(Figs. 4, 5 and 6.)

From the transfer and straightening apparatus of Fig. 4, the flat sheets are delivered to a chain conveyer 431 driven by sprockets 432 secured to shaft 400. This 50 chain carries the sheets forward through an air-cooled chamber (Fig. 5) and finally delivers them through a "fixing" bath to the auxiliary flattening machine. (Fig. 7.)

Chain conveyer 431 is of special design, 55 as shown in Figs. 32, 33, 34 and 35, and comprises a pair of parallel chains 433 and 434 tied together by flights 435, each of which has flattened ears 436 and 437 at its ends for bolted connection with ears on the 60 chain links. Each flight has a pair of up-standing lugs 438 and horizontal cross-bars 439 staggered with respect to corresponding bars on adjacent flights. These cross-bars and likewise the flights themselves and their

upstanding lugs 438 are brought to a knife-edge wherever they would contact with the metal sheets to be transported. Cross-bars 439 have their top edges crowned somewhat particularly near the ends, so that in passing over sprockets 432 there will be formed 70 an approximately cylindrical skeleton surface, as shown in Fig. 35, on which the sheets can be received. The ends of bars 439 will not dig into the coating nor mar the under-surface of the sheet. 75

The casing for the air-cooled chamber (Fig. 5) comprises a plurality of sheet metal sections 440, as shown in Figs. 37 and 38, and these sections have abutting flanges by which they may be bolted together on gaskets to make the chamber air tight. Within this rectangular casing, as shown in Fig. 37, angle bars 441 are fastened to the side walls to form shelves on which the rollers of the chain conveyer 431 may travel, and 80 similar angle bars 442 support the lower returning chains. 85

The discharge end of the air-cooled chamber is provided with a hood 443, (Fig. 6), the lower edge of which dips below the surface 90 of a body of oil 444 contained in a suitable tank, thereby sealing the air-cooled chamber against the entrance of air from the discharge end of the apparatus. This oil 444 may be a light paraffin oil of say 350 flash 95 test, and of a character to prevent tarnishing of the sheets during shipment or storage.

In order that the sheets and their supporting conveyer may dip beneath the surface of the body of oil 444, the upper strands of 100 the conveyer loop pass over sprockets 445 (Fig. 5) and then turn downward toward the oil bath and pass under submerged sprockets 446 (Fig. 6) and then upward over sprockets 447 at which the oiled sheets 105 are delivered to the auxiliary flattening apparatus of Fig. 7. On its return movement, the conveyer dips again beneath the surface of the oil to pass under sprockets 448 and then upward over sprockets 449 mounted 110 within the air-cooled chamber.

Each pair of sprockets over which the chains of this conveyer pass, are rigidly connected together through a suitable cross-shaft, so that both sides of the conveyer will 115 move in unison, and at the tail end of the conveyer the shaft 450 for sprockets 447 is mounted in take-up bearings of usual type, whereby the tension of the conveyer chains may be regulated. In Fig. 5 the bearing 120 supports for sprockets 445 and 449 are housed within the air-tight casing so that there may be no leakage of air, and access may be had to these sprockets through man-holes 451 and 452. At this part of the air-cooled chamber the casings 440 are wider, as shown in Fig. 36, to give room for the 125 sprocket shafts and their bearings, and the

bottoms of the sections slope downward gradually toward the oil bath 444 to facilitate return thereto of the oil dripping from the conveyer when it leaves the cooling oil bath.

Inclined angle bars 453 and 454 (Fig. 6) guide and support the upper chains of the conveyer during their movement into and out of the oil and similar angle bars guide 10 and support the returning strands.

Auxiliary flattening machine.

(Figs. 7, 7^A and 40.)

The final or auxiliary flattening machine 15 of Fig. 7 is driven from a sprocket 455 (Fig. 39) on shaft 450. The machine comprises a frame 456 above which is adjustably mounted a train of flattening rolls 457, the height of which at either or both ends 20 is determined by the bolts 458 and their operating slots. In front of these flattening rolls are a pair of composition rolls 459 and 460 which are carried by shafts 461 and 462, respectively and serve as press rolls. 25 These shafts have their bearing blocks slidingly mounted in forked guides 463 and 464, each of which is adjustably bolted to frame 456 by bolts 465. The lowermost roll 459 is adjustable up or down by means of a 30 pair of jacks 466, each of which bears against a bearing block for shaft 461 and is screw-threaded into the body of the bearing guide. The top roll 460 floats on the lower roll with which it has geared connection 35 through a gear 467 on shaft 462, and a similar gear 468 on shaft 461. Shaft 461 of the lower composition roll carries a sprocket 469 which is driven through a chain 470 from sprocket 455 at the tail of 40 the conveyer. (Fig. 39.)

When the sheets come from the fixing oil bath (Fig. 6,) and are delivered over the tail of that conveyer, they may be slightly curved or warped as the result of their decrease in temperature during transit through 45 the air-cooled chamber, or they may have some kink or curvature from their passage through the oil bath. On delivery by the conveyer they pass over the apron 471 and 50 between the composition rolls 459 and 460, which serve as press rolls to squeeze off any excess of oil and deliver the sheets into the gang of flattening rolls which in usual manner straighten them out perfectly flat and 55 pass them on to such further conveying, or other apparatus, as may be used. The train of flattening rolls, Fig. 7^A, is driven through a sprocket 472 and chain 473 from a large sprocket 474 carried on shaft 461 of the 60 lower composition roll.

The furnace conveyer.

(Figs. 1 to 4 and 17 to 20.)

The furnace conveyer, whereby the sheets

are taken, from the coating machine and its transfer mechanism, and delivered into and through the furnace muffle, and the upper water-cooled chamber, is of special construction, as shown in Figs. 17 to 20, inclusive. The conveyer comprises two parallel chains 70 each of which consists of parallel links 475 and 476 connected at their ends by transverse pins 477 on each of which is a roller whereon the chain may travel. Each alternate inner link 475 has a laterally projecting ear 478 and to this and the corresponding ear of the opposing link is secured by bolts 479 the horizontally bent ears of a conveyer flight 480. Each flight comprises a horizontal bar with upturned ends 481, the inner edges of which are knife edges. Adjacent these knife edges, the outer ends of the horizontal bar are shaped to knife edges at 482 (Fig. 18). These flights are considerably wider than the pair of chains by 85 which they are driven and are carried well above the chain rollers by the supporting ears at which they are bolted to the chains.

By making these conveyer flights with knife edges, as shown and described, they 90 have but limited area of contact with the arched sheets delivered to the conveyer by the converging conveyer and pusher of Fig. 45, and although the furnace conveyer flights engage the arched sheets only at their 95 edges, they securely hold those sheets in arched form during transportation through the muffle, and through the water-cooled chamber. Within the muffle both sides of the sheet are freely exposed to the heating 100 and other actions which there go on, and in the muffle as well as in the cooling chamber, the temperatures above and below the arched sheet are substantially the same. The flights for the furnace conveyer, furthermore, offer 105 no appreciable impediment to the release of the arched sheets by the stripping apparatus of Fig. 4.

The furnace is of such massive design that when once brought to working temperature it should be kept in continuous operation, and to prevent local over-heating of the furnace conveyer, it should be kept in motion whenever the muffle is at working temperature, so that the periodic immersions of the flights and their supporting rollers in the water bath of Fig. 3, together with the cooling effect of the water-cooled chambers, may keep the temperature of the chain down to a safe value. No track or 110 guideway is provided within the furnace muffle and the chain is allowed to roll along over the floor of the muffle, but there is a trackway 483 (Figs. 1, 2 and 47) leading up to the intake end of the muffle and consisting 115 of a pair of angle bars adjustably supported as shown.

When the conveyer leaves the muffle and passes into the water-cooled chamber, it is received in a guideway (Fig. 27) afforded by upstanding webs 484 integral with the inner wall 334 of the water-cooled sections. The direct contact between the rollers and the water-cooled inner wall contributes to effective cooling of the conveyer. The first and each succeeding section of the series, as shown in Fig. 24, has its webs 484 curved outward at 485 to form a flaring mouth for the better guidance of the furnace conveyer, which, along its upper length or half is pushed rather than pulled through the muffle.

After passing to the transfer box of Fig. 4, and on entering the lower water-cooled chamber, the returning flights and chains are supported on shelves 486 (Fig. 28) formed by L-shaped webs integral with the inner wall of the water-cooled castings. The good thermal conductivity of these webs is of advantage. Over these shelves the chains roll until (Fig. 3) they pass over the special sprocket 428 and down into the water-cooling bath 427, where they pass over submerged sprockets 487 mounted on a shaft carried by suitable inverted brackets 488 which at their upper ends are suitably fastened to angle bars 426.

The furnace conveyer next passes upward out of the water bath and over the second pair of special sprockets 489 and then up an incline to a track 490 (Figs. 22 and 28) which runs forward through the conduit 305 of the furnace and terminates near a pair of sprockets 491 (Fig. 1), the shaft of which is mounted in take-up bearings, whereby the tension of the chain may be regulated.

The drive.

All of the moving elements above described are preferably driven by a single prime mover such as a variable speed electric motor 492 (Fig. 47). This motor is provided with a pinion 493 meshing with a spur gear 494 on one end of a transverse shaft 495, the other end of which carries a pinion 496 meshing with a spur gear 497 on a second transverse shaft 498 on which the driving sprockets 499 for the furnace conveyer are fastened. This shaft 498 also carries a gear 500 which meshes with a gear 501 on a stub shaft 502 (Fig. 45) and it is from this stub shaft and its sprocket 503 that the coating machine and the converging conveyer and pusher are driven through chain 178, as heretofore described.

The furnace conveyer chains are utilized for transmitting power to their tail shaft 397 (Fig. 4) through the sprockets 422 secured thereto. The driving connections

from shaft 397 to the elements which lie beyond have already been described.

By thus driving all of the machines and mechanisms from a single motor, all of the moving elements are properly timed in their movements and the coated sheets travel through at a definite and predetermined rate and one best suited to the changes which are to be effected within the furnace. By using a variable speed motor the time of transit through the furnace can be changed to suit changes in gage of the sheets under treatment or variations in the duration of treatment as occasion may require. The coating machine can be unclutched and stopped while the furnace conveyer continues to travel through the furnace and the flattening rolls and their adjuncts can also be stopped while sheets are still coming through the furnace. All of the clutches are of the single jaw type to insure correct timing of the several parts after each disconnection and reconnection of the clutches. Convenience of operation and flexibility of control are thereby assured.

The foregoing description sets forth in considerable detail the apparatus as actually constructed without attempting to define the permissible variations in the equipment as a whole, or in the details of its several machines and mechanisms. I am, however, aware that the apparatus may be changed in many particulars without departing from the spirit of my invention as defined by the appended claims.

In a copending application Serial No. 106,564, filed June 29, 1916, claims are made on the delivery mechanism whereby the sheets as they come from the coating machine are bent into arched form and are delivered to the furnace conveyer, and in my copending application, Serial No. 125,536, filed October 14, 1916, claims are made on novel features of the coating machine *per se*.

I claim:

1. In an apparatus for plating metal with metal, the combination of a furnace, means for maintaining sheets of metal in arched form, and for delivering said sheets into said furnace for treatment therein.
2. In an apparatus for plating metal with metal, the combination of a furnace, means for maintaining sheets of elastic metal in arched form, and for delivering said sheets to and through said furnace for treatment within the furnace.
3. In an apparatus for plating metal with metal, the combination of a furnace having an inlet at one end and an outlet at the other end, means for maintaining sheets of metal in arched form and for delivering said sheets to said inlet and through said furnace to said outlet for treatment within the furnace.

- while said sheets are supported only at their edges.
4. In an apparatus for plating metal with metal, the combination of a furnace, having a muffle, and a conveyer movable through said muffle, said conveyer having means for holding arched sheets of elastic metal by their edges during transit through said muffle.
5. In an apparatus for plating metal with metal, the combination of a furnace, having a muffle open at both ends, and a conveyer traveling along the bottom of said muffle and having means for holding arched sheets of elastic metal by their edges only during transit through said muffle.
6. In an apparatus for plating metal with metal, the combination of a furnace having an inlet at one end and an outlet at the other end, a cooling chamber beyond said outlet and means for maintaining elastic sheets of metal in arched form and for delivering said sheets to said inlet and through said furnace into said cooling chamber, substantially as described.
7. In an apparatus for plating metal with metal, the combination of a furnace having a muffle, a cooling chamber into which the rear end of the muffle opens, and a conveyer movable through said muffle and chamber, said conveyer having means for holding arched sheets of elastic metal by their edges during transit through said muffle.
8. In an apparatus for plating metal with metal, the combination of a furnace having a muffle, a cooling chamber beyond said muffle, and a conveyer traveling along the bottom of said muffle and having means for holding arched sheets of elastic metal by their edges only during transit through said muffle and cooling chamber.
9. In an apparatus for plating metal with metal, the combination of a furnace, having a muffle open at both ends, and a conveyer traveling through said muffle, said conveyer having rollers which rest on the bottom of the muffle and having flights with knife edges, affording but limited area of contact with sheets of metal to be transported through the muffle.
10. In an apparatus for plating metal with metal, the combination of a furnace having a muffle, and a continuous conveyer movable through said muffle, said conveyer having parallel chains with rollers and having flights spaced apart along the chains, said flights having knife-edged lugs to grip the edges of an arched sheet of elastic metal and hold it in arched shape during transit through the muffle.
11. In an apparatus for plating metal with metal, the combination of a furnace, having a muffle, an endless conveyer movable through said muffle, said conveyer comprising parallel chains having rollers which rest on the floor of the muffle and roll thereover, said conveyer chains being tied together by flights, the outer and upturned ends of which are shaped to form knife edges to grip the edges of arched sheets of elastic metal and hold the sheets in arched shape during transit through the muffle, substantially as described.
12. In an apparatus for plating metal with metal, the combination of a furnace having a muffle, a conveyer traveling through said muffle, a cooling chamber connected to the rear end of said muffle and into which said conveyer passes, said chamber comprising a plurality of hollow sections, each having an inlet and an outlet for the circulation of a cooling liquid through the section.
13. In an apparatus for plating metal with metal, the combination of a furnace having a muffle, a conveyer traveling through said muffle, a cooling chamber connected to the rear end of said muffle and into which said conveyer passes, said chamber comprising a plurality of hollow sections, each having an inlet and an outlet for cooling fluid, and a baffle for directing the fluid around the section.
14. In an apparatus for plating metal with metal, the combination of a furnace, a conveyer traveling through said furnace, a water cooled chamber to the rear of said furnace into which said conveyer passes, said chamber comprising a plurality of hollow sections supported end to end and each free to move endwise to accommodate thermal expansions or contractions of adjacent sections.
15. In an apparatus for plating metal with metal, the combination of a furnace, a conveyer traveling through said furnace, a water cooled chamber to the rear of said furnace into which said conveyer passes, said chamber comprising a plurality of hollow sections having flanges by which they are secured end to end, each of said sections being independently removable for inspection or repair.
16. In an apparatus for plating metal with metal, the combination of a furnace, a conveyer traveling through said furnace, a water cooled chamber to the rear of said furnace into which said conveyer passes, said chamber comprising a plurality of hollow sections, each of which has an inlet and an outlet at the top and an emergency outlet at the bottom.
17. In an apparatus for plating metal with metal, the combination of a furnace, a conveyer traveling through said furnace, a water cooled chamber to the rear of said furnace into which said conveyer passes, said chamber comprising a plurality of hollow sections.

low sections with flanges by which they are secured end to end, each of said sections having a plurality of water inlets spaced apart and an outlet, and a baffle for directing the water from said inlets entirely around the section, substantially as described.

18. In an apparatus for plating metal with metal, the combination of a furnace, a conveyer traveling through said furnace, a water cooled chamber to the rear of said furnace into which said conveyer passes, said chamber comprising a plurality of hollow sections with flanges by which they are secured end to end with air-tight joints, supporting means for said sections permitting endwise movement of any section to accommodate thermal expansions or contractions of adjacent sections, each of said sections being independently removable for inspection or repair and having at its top a plurality of water inlets spaced apart and a plurality of outlets spaced apart, and having at its bottom an emergency outlet, with a baffle between the inlets and outlet to direct the cooling water entirely around the section, substantially as described.

19. In an apparatus for plating metal with metal, the combination of a furnace, a conveyer traveling through said furnace, a water cooled chamber to the rear of said furnace into which said conveyer passes, said chamber comprising a plurality of hollow sections supported end to end and each of said sections having webs forming a guide for said conveyer.

20. In an apparatus for plating metal with metal, the combination of a furnace, a conveyer traveling through said furnace, a water cooled chamber to the rear of said furnace into which said conveyer passes, said chamber comprising a plurality of hollow sections supported end to end, and each of said sections having upstanding integral webs which abut against the webs of adjacent sections to form a continuous guide for said conveyer.

21. In an apparatus for plating metal with metal, the combination of a furnace having a muffle, a conveyer traveling through said muffle and having supporting rollers, a water cooled chamber connected to the rear end of said muffle and into which said conveyer passes, said chamber comprising a plurality of sections each having an inner and an outer wall, and means for circulating water between said walls, said conveyer rollers contacting directly with said inner water cooled walls, substantially as described.

22. In an apparatus for plating metal with metal, the combination of a furnace, a conveyer traveling through said furnace, a cooling chamber to the rear of said furnace into which said conveyer passes, receiving means to which said conveyer discharges the trans-

ported articles, a second cooling chamber 65 through which said conveyer passes on its return toward the front of the furnace, and a water bath sealing said second cooling chamber and into which said conveyer passes.

23. In an apparatus for plating metal with metal, the combination of a furnace, a conveyer traveling through said furnace, a cooling chamber to the rear of said furnace into which said conveyer passes, receiving means to which said conveyer discharges the transported articles, a second cooling chamber 75 through which said conveyer passes on its return toward the front of the furnace, a hood at the end of said second chamber and a body of water forming a seal for said hood 80 and into which said conveyer passes.

24. In an apparatus for plating metal with metal, the combination of a furnace, a conveyer traveling through said furnace, a cooling chamber to the rear of said furnace into 85 which said conveyer passes, receiving means to which said conveyer discharges the transported articles, a second cooling chamber through which said conveyer passes on its return toward the front of the furnace, a hood 90 at the end of said second chamber, sprockets in said hood over which said conveyer makes a reverse bend and travels downward, a body of water sealing the lower end of said hood and into which said conveyer passes, 95 and a conduit through which the water-cooled conveyer returns to the front of the furnace.

25. In an apparatus for plating metal with metal, the combination of a furnace, a conveyer traveling through said furnace, a cooling chamber to the rear of said furnace into which said conveyer passes, a receiving chamber within which said conveyer discharges the transported articles, and a water 100 bath into which said conveyer passes on its way to the front of the furnace, said bath serving as a seal for said receiving chamber.

26. In an apparatus for plating metal with metal, the combination of a furnace, a conveyer passing through said furnace, means 110 for delivering elastic arched sheets of metal to said conveyer for delivery to and through said furnace and receiving means whereon said arched sheets are automatically delivered by said conveyer.

27. In an apparatus for plating metal with metal, the combination of a furnace, a conveyer passing through said furnace, means for delivering elastic arched sheets of metal 120 to said conveyer for delivery to and through said furnace, and means for stripping the arched sheets from the conveyer.

28. In an apparatus for plating metal with metal, the combination of a furnace, a conveyer passing through said furnace, means for delivering arched sheets of metal to said conveyer for delivery to and through said

- furnace, means for stripping the arched sheets from the conveyer and means for forwarding the sheets beyond the stripping means.
5. 29. In an apparatus for plating metal with metal, the combination of a furnace, a conveyer passing through said furnace, means for delivering arched sheets of metal to said conveyer for delivery to and through said furnace, and means for stripping the arched sheets from the conveyer and for forwarding and flattening said sheets.
10. 30. In an apparatus for plating metal with metal, the combination of a furnace, a conveyer passing through said furnace, means for delivering arched sheets of metal to said conveyer for delivery to and through said furnace, a receiving apron having a nose for stripping the arched sheets from the conveyer, a pusher which advances said sheets beyond said nose and means for flattening said sheets, substantially as described.
15. 31. In an apparatus for plating metal with metal, the combination of a furnace, a conveyer passing through said furnace, means for delivering sheets of metal to said conveyer for delivery to and through said furnace, a receiving apron to which said sheets are delivered by said conveyer, and pushing mechanism for advancing said sheets along said apron, said mechanism being adapted for movement to inoperative position when desired.
20. 32. In an apparatus for plating metal with metal, the combination of a furnace, a conveyer passing through said furnace, means for delivering sheets of metal to said conveyer for delivery to and through said furnace, means for stripping the sheets from the conveyer, means for flattening said sheets, and pusher mechanism for advancing said sheets toward said flattening means, said pusher mechanism being pivotally mounted and adapted to swing upward out of operative engagement with the sheets when their advancement to the flattening means is not desired.
25. 33. In an apparatus for plating metal with metal, the combination of a furnace, a conveyer traveling through said furnace, a cooling chamber to the rear of said furnace into which said conveyer passes, receiving means to which the articles carried by said conveyer are delivered, and a water cooled box inclosing said receiving means.
30. 34. In an apparatus for plating metal with metal, the combination of a furnace, a conveyer traveling through said furnace, a cooling chamber to the rear of said furnace into which said conveyer passes, receiving means to which the articles carried by said conveyer are delivered, means for water cooling said receiving means, and means for preventing circulation of air through said cooling chamber toward said furnace.
35. 35. In an apparatus for plating metal with metal, the combination of a furnace, means for delivering arched sheets of metal to and through said furnace for treatment therein while supported only at their edges, a cooling chamber into which said sheets pass from said furnace, means for receiving, forwarding and flattening said sheets, a second cooling chamber, a conveyer therein to which said flattened sheets are delivered, and means for sealing said last-named chamber against free circulation of air therein.
40. 36. In an apparatus for plating metal with metal, the combination of a furnace having a muffle open at both ends, a conveyer traveling through said muffle and having means for holding arched sheets of elastic metal by their edges only during transit through said muffle, a water cooled chamber beyond said muffle, an air cooled chamber, a conveyer therein, means between said cooled chambers for stripping the sheets from the furnace conveyer, for flattening them and for delivering them in flat form to the other conveyer, and an oil bath at the end of said air cooled chamber into which said sheets are delivered.
45. 37. In an apparatus for plating metal with metal, the combination of a furnace having a muffle open at both ends, a conveyer traveling through said muffle and having means for holding arched sheets of elastic metal by their edges only during transit through said muffle, a water cooled chamber beyond said muffle, an air cooled chamber, a conveyer therein, means between said cooled chambers for stripping the sheets from the furnace conveyer, for flattening them and for delivering them in flat form to the other conveyer, and an oil bath at the outlet end of said air cooled chamber into which the sheets are carried.
50. 38. In an apparatus for plating metal with metal, the combination of a furnace having a muffle open at both ends, a conveyer traveling through said muffle and having means for holding arched sheets of elastic metal by their edges only during transit through said muffle, a water cooled chamber beyond said muffle, an air cooled chamber, a conveyer therein, means between said cooled chambers for stripping the sheets from the furnace conveyer, for flattening them and for delivering them in flat form to the other conveyer, an oil bath at the outlet end of said air cooled chamber into which the sheets are carried, and finishing means beyond said bath to which said sheets are conveyed.
55. 39. In an apparatus for plating metal with metal, the combination of a furnace having a muffle open at both ends, a conveyer traveling through said muffle and having means for holding arched sheets of

elastic metal by their edges only during transit through said muffle, a water cooled chamber beyond said muffle, an air cooled chamber, a conveyer in said air cooled chamber, means between said cooled chambers for stripping the sheets from the furnace conveyer, for flattening them and for delivering them in flat form to the other conveyer, a bath at the outlet end of said air cooled chamber serving as a seal and into and out of which the sheets are carried, and finishing means beyond said bath to which said sheets are conveyed, said finishing means comprising press rolls and a train of flattening rolls through which said sheets are passed.

40. In an apparatus for plating metal with metal, the combination of a furnace, a conveyer passing through said furnace, means for delivering arched sheets of metal to said conveyer for delivery to and through said furnace, receiving means whereon said arched sheets are delivered by said conveyer and a pusher for advancing the sheets thus delivered, said pusher comprising an endless chain with pushing fingers, and the supporting means for said chain being movable toward or from the receiving means to render said pushing fingers active on the sheets or inactive thereon as desired.

41. In an apparatus for plating metal with metal, the combination of a furnace, a conveyer passing through said furnace, means for delivering arched sheets of metal to said conveyer for delivery to and through said furnace, receiving means whereon said arched sheets are delivered by said conveyer and a pusher for advancing the sheets thus delivered, said pusher comprising a pair of chains with cross-bars carrying pushing fingers arranged to contact with the rear of each sheet near its side edges, means for driving said chains and means for lifting said chains upward bodily to render the pushing fingers inactive when desired.

42. In an apparatus for plating metal with metal, the combination of a furnace, a conveyer passing through said furnace, means for delivering arched sheets of metal to said conveyer for delivery to and through said furnace, receiving means whereon said arched sheets are delivered by said conveyer and a pusher for advancing the sheets thus delivered, said pusher comprising a pair of chains with cross-bars carrying pushing fingers arranged to contact with the rear of each sheet near its side edges, means for driving said chains and means for lifting said chains upward bodily, whether said chains are traveling or not, to render said pushing fingers inactive on the sheets.

43. In an apparatus for plating metal with metal, the combination of a furnace, a conveyer passing through said furnace, means for delivering arched sheets of metal

to said conveyer for delivery to and through said furnace, receiving means whereon said arched sheets are delivered by said conveyer and a pusher for advancing the sheets thus delivered, said pusher comprising a pair of chains with cross-bars carrying pushing fingers arranged to contact with the rear of each sheet near its side edges, means for driving said chains, a water cooled box wherein said receiving and pushing means are housed, and means operative from the outside of the box for manually lifting the pusher out of operative engagement with the advancing sheets.

44. In an apparatus for plating metal with metal, the combination of a furnace, a conveyer passing through said furnace, means for delivering arched sheets of metal to said conveyer for delivery to and through said furnace, receiving means whereon said arched sheets are delivered by said conveyer and a pusher for advancing the sheets thus delivered, said pusher comprising endless chains with flights having fingers for engaging each sheet as it advances, said chains being mounted on floating arms which are manually movable upward to prevent contact of said fingers with said sheets, and means for driving said pusher chains whether the fingers are or are not in position for operative engagement with said sheets.

45. In an apparatus for plating metal with metal, the combination of a furnace, means for delivering arched sheets of metal to and through said furnace for treatment therein while supported only at their edges, a cooling chamber into which said sheets pass from said furnace, means for receiving, forwarding and flattening said sheets, a second cooling chamber and a conveyer therein to which said flattened sheets are delivered, said conveyer having flights presenting knife edges on which said flattened sheets are received and transported, substantially as described.

46. In an apparatus for plating metal with metal, the combination of a furnace, means for delivering arched sheets of metal to and through said furnace for treatment therein while supported only at their edges, a cooling chamber into which said sheets pass from said furnace, means for receiving, forwarding and flattening said sheets, a second cooling chamber and a conveyer therein to which said flattened sheets are delivered, said conveyer having flights presenting knife-edges on which said flattened sheets are received and transported, and means for sealing said last-named chamber against free circulation of air therein.

47. In an apparatus for plating metal with metal, the combination of a furnace, means for delivering arched sheets of metal to and through said furnace for treatment therein while supported only at their edges,

- a cooling chamber into which said sheets pass from said furnace, means for receiving, forwarding and flattening said sheets, a second cooling chamber and a conveyer 5 therein to which said flattened sheets are delivered, said conveyer having flights with cross-bars having sharp and rounded top edges to receive and transport said flattened sheets without marring the surface thereof.
- 10 48. In an apparatus for plating metal with metal, the combination of a furnace, a conveyer mounted to travel through said furnace for transporting articles to be heated therein, a cooling chamber and a 15 cooling bath through which said conveyer passes, a prime mover for driving said conveyer, receiving and flattening means to which the articles are delivered from the cooling chamber, a driving connection between said last-named means and said conveyer, and clutch mechanism for interrupting said connection when desired.
49. In an apparatus for plating metal with metal, the combination of a furnace in 20 which the articles to be coated are heated, a conveyer traveling through said furnace, a cooling chamber and a water bath to the rear of said furnace and through which said conveyer passes, a prime mover for driving said conveyer, means for receiving, forwarding and flattening articles delivered from said conveyer, a driving connection between said last-named means and said conveyer, a second cooling chamber, a conveyer there- 25 in, and means for driving said last-named conveyer by power delivered through said furnace conveyer, substantially as described.
50. In an apparatus for plating metal 30 with metal, the combination of a furnace, an endless conveyer for transporting arched sheets of metal through said furnace to be heated thereby, a water-cooled chamber to the rear of said furnace through which said conveyer passes, an air-cooled chamber, a conveyer therein, flattening rolls and pushing mechanism between said conveyers for transferring the sheets from one conveyer to the other, and driving connections be- 35 tween said furnace conveyer, said pusher, said flattening rolls and said second conveyer, whereby their movements are timed in accordance with the lineal speed of said furnace conveyer.
- 55 51. In an apparatus for plating metal 40 with metal, the combination of a furnace, a conveyer movable through said furnace and adapted to hold arched sheets of elastic metal by their edges only, means for coating flat sheets of metal with a viscous covering, means for shaping each sheet into arched form and delivering it to said conveyer for transmission through said furnace, a cooling chamber beyond said fur- 45 nace into which said conveyer passes, and receiving means on which said arched sheets are delivered.
52. In an apparatus for plating metal with metal, the combination of a furnace, a conveyer movable through said furnace and adapted to hold arched sheets of elastic metal by their edges only, means for coating flat sheets of metal with a viscous covering, means for shaping each sheet into arched form and delivering it to said conveyer for transmission through said furnace, a cooling chamber beyond said furnace into which said conveyer passes, and means beyond said cooling chamber for receiving, forwarding and flattening said sheets.
53. In an apparatus for plating metal with metal, the combination of a furnace, a conveyer movable through said furnace and adapted to hold arched sheets of elastic metal by their edges only, means for coating flat sheets of metal with a viscous covering, means for shaping each sheet into arched form and delivering it to said conveyer for transmission through said fur- 50 nace, a cooling chamber beyond said furnace into which said conveyer passes, a second cooling chamber, a conveyer therein, and means between said conveyers for receiving, forwarding and flattening said metal sheets.
54. In an apparatus for plating metal with metal, the combination of a furnace, a conveyer movable through said furnace and adapted to hold arched sheets of elastic metal by their edges only, means for coating flat sheets of metal with a viscous covering, means for shaping each sheet into arched form and delivering it to said conveyer for transmission through said furnace, a cooling chamber beyond said furnace into which said conveyer passes, a second cooling chamber, a conveyer therein, means between said conveyers for receiving, forwarding and flattening said metal sheets, and an oil bath sealing said second cooling chamber and through which said sheets are delivered.
55. The combination with a furnace and an endless conveyer, arranged to pass therethrough, of a pair of receiving guides located at the receiving end of said conveyer, means for delivering a series of objects to said receiving guides, and an endless pusher chain provided with a series of fingers adapted to strike each of the objects as it rests in the receiving guides, and push them onto the furnace conveyer at regular intervals in the progress of the conveyer.
56. The combination with a furnace and an endless conveyer arranged to carry a series of flexible sheets therethrough while said sheets are supported at their edges only,

a pair of stationary receiving guides located at the receiving end of said conveyer and spaced apart a distance approximately equal to the span of the sheets while supported at 5 their edges only on said conveyer, and an endless pusher chain provided with fingers

arranged to strike the rear end of each sheet while it is in the stationary guides and push said sheet through said guides onto said conveyer.
